INSULATING MACHINE

John M. Biddison, Dayton, Ohio, assignor to

Harry W. Moore, Dayton, Ohio

Original application Aug. 20, 1953, Ser. No. 375,523, now Patent No. 2,835,372, dated May 29, 1958. Divided and this application Apr. 10, 1958, Ser. No. 727,728

6 Claims. (Cl. 29—205)

This invention relates to an automatic machine for performing work upon articles of manufacture. It relates particularly to a machine for insulating the slots of armature cores. However, the invention is not so limited, in that it may be employed for insulating stators or other elements of an electrical machine and may also be used for other purposes.

This application is a division of my copending application Serial No. 375,523, filed August 20, 1953 for Insulating Machine, now Patent No. 2,835,372.

An object of this invention is to provide an automatically operating machine for insulating coil receiving slots.

Another object of this invention is to provide a machine which receives armatures to be insulated from a source of supply, insulates the slots of each individual armature and then places each armature upon a conveyor or a set of rails upon which it moves from the machine.

Another object is to provide an automatic insulating machine which can be used in a large automatic insulating and winding system in which several insulating and winding machines are employed to their full capacity.

Another object of this invention is to provide an efficient system used in manufacturing electrical devices so as to reduce the cost of production without reducing quality.

Other objects and advantages reside in the construction of parts, the combination thereof and the mode of operation, as will become more apparent from the following description.

Referring to the drawings, FIGURE 1 is a fragmentary perspective view disclosing the principal carrier elements of the preferred embodiment of an insulating machine of this invention.

FIGURE 2 is a fragmentary side elevational view showing the operating mechanism of the preferred embodiment of the automatic insulating machine of this invention.

FIGURE 3 is a fragmentary side elevational view of the engaging device which directs an insulated armature to the rails upon which the armature moves from the machine.

FIGURE 4 is a fragmentary sectional view disclosing elements of the machine performing a step in the formation of the insulating material into the proper shape to enter an armature slot.

FIGURE 5 is a fragmentary side elevational view disclosing elements of the machine performing the next step in the formation of the insulating material into the proper shape to enter an armature slot.

FIGURE 6 is a fragmentary sectional view disclosing means of inserting a properly formed strip of insulation into an armature slot.

FIGURE 7 is a fragmentary side sectional view disclosing the means provided by this invention for rotat-

2

tively indexing an armature retained in the insulating machine, so that consecutive armature slots are insulated.

FIGURE 8 is a fragmentary side view, a portion of which is in section, of a preferred modification of an automatic insulating machine of this invention.

FIGURE 9 is a sectional view, taken substantially on the line 9—9 of FIGURE 8.

FIGURE 10 is a fragmentary perspective view showing the clamping means by which an armature is retained during the insulating process according to the preferred modification of this invention.

Referring to the drawings in detail, reference numeral 18 indicates the housing of the preferred embodiment of the insulating machine. The machine is adapted to insulate any conventional armature core 20 having a shaft 22 and slots 24.

A plurality of armature cores 20 approach the housing 18 rolling upon a pair of inclined rails 28, which are partially supported by the housing 18. An arm 30 having two substantially right angle portions irregular in shape is provided with an arcuate recess in the upper end thereof and is pivotally attached by means of a pin 31 to the housing 18. The arcuate recess is adapted to receive an armature core 20, as clearly disclosed in FIGURES 1, 2 and 3.

Movement of the arm 30 is actuated by a hydraulic motor 32, which is attached to the housing 18 adjacent the arm 30. A conduit 34 serves to connect the hydraulic motor 32 to a source of hydraulic fluid. Pivotally attached at the mid portion of the arm 30 and to the end of a piston rod 36 of the hydraulic motor 32 is a link rod 40, which is encircled by an elongate helical spring 42. Also, pivotally attached at the end of the piston rod 36 and held by a pin 37 is a brace 44, which is pivotally supported upon the housing by means of an extension 46. The rod 40 and the brace 44 cooperate to form a toggle mechanism actuating the arm 30.

As the piston rod 36 is extended by the hydraulic motor 32, the link rod 40, with the spring 42, forces the arm 30 to pivot about the pin 31. The spring 42 cushions the movement of the link rod 40 against the arm 30. An armature core 20 is thereby carried upwardly in the arcuate recess of the arm 30 into an arcuate chuck or clamping recess 50 and the armature core 20 is held in the clamping recess 50 by the arm 30, as shown in FIGURE 2.

As the armature core 20 is moved to the chuck 50 it engages a pair of pivotally mounted fingers 51 which are retained upon a pin 52 and resiliently held in the position as shown in FIGURES 1, 2, and 3 by a spring 53. The fingers 51 are rotatably pushed upwardly as they are engaged by the moving armature core 20 and when the armature core 20 has reached the chuck 50 the fingers 51 are resiliently returned to the normal position by the spring 53. The purpose of the fingers 51 will be discussed below.

A projection 54, attached above the chuck or clamping recess 50 and extending over the clamping recess 50, retains the armature core 20 from longitudinal movement while it is held in the chuck or clamping recess 50 by the arm 30. As each armature core 20 is thus retained in the chuck or clamping recess 50, a strip of insulating material is automatically inserted into each slot 24.

Within the housing 18 immediately behind the chuck

50 are means, shown in FIGURES 4, 5, and 6 for inserting a strip of insulation into each slot 24 of the armature core 20. A continuous strip of insulation 55 passes into a slot 56 and moves a measured distance equal to the length of a slot 24 of the armature core 20. The strip 55 is then cut, establishing the proper length thereof. A plunger 58 forces the cut strip 55 downwardly upon a bottom die 60. Side dies 62 shown in FIGURE 4 bend the edge portions of the cut strip 55 upwardly and cause the cut strip 55 to assume substantially a square U shape as it rests against the bottom die 60.

Then a ram 64, movable longitudinally in a slot 66, forces the U-shape cut strip 55 through a funnel 70 and into a slot 24 of the armature core 20, which is retained in the chuck 50 by the arm 30 adjacent the smaller end of the funnel 70. As the cut strip of insulation 55 is forced through the funnel, the upper ends of the vertical edges are bent inwardly. As best shown in FIGURE 7, the edges of the strip material 55 near the periphery of the armature core 20 are bent inwardly. The strip of insulation is composed of a material which tends to "spring back" into its original shape after being bent and the strip of insulation thus attempts to "spring" outwardly and thereby fits itself firmly against the entire inner walls of the slot 24 as the strip is pushed through the funnel 70 and into the slot.

After a slot 24 of the armature core 20 receives a strip of insulation, the armature core 20 is rotated by an indexing means, so that another slot 24 of the core 20 is in alignment with the funnel 70. Within a head 72 of the housing 18 is a reciprocally operable inner carriage 74. Pivotedly mounted upon the inner carriage 74 is a pawl 76. Upon each return stroke of the ram 64, the inner carriage 74 is forced to move within the head 72 by a roller 80 as the roller 80 engages a movable cam 82. The inner carriage 74 is joined to the cam 82 by a bolt 86 which operates within a slot 88 of the head 72. The inner carriage 74 moves an exact and proper distance upon each stroke so that the armature core 20 is indexed to the proper extent upon each operation. The clamping in action of the arm 30, as it retains an armature core 20 in the chuck 50, is sufficiently loose to permit sliding rotational action of the armature core 20 within the chuck 50 as the armature core 20 is rotatively indexed by the pawl 76.

After all of the slots 24 of the armature core 20 are provided with insulation, automatic switch means cause the hydraulic motor 32 to retract the piston rod 36 inwardly and thereby rotate the arm 30 downwardly. As the armature core 20 is moved downwardly by the arm 30, it again engages the pair of fingers 51. A catch (not shown) prevents the fingers 51 from rotating further counterclockwise than the position shown in FIGURES 1, 2 and 3. Therefore, as the insulated armature core 20 is moved downwardly by the arm 30, the shaft 22 of the core 20 engages the fingers 51 which thereby prevent the insulated armature core 20 from moving lower as the arm 30 moves lower, as shown in FIGURE 3.

The arm 30 then returns to its position at the end of the rails 28 without the armature core which has been insulated. Each insulated armature core rolls downwardly upon inclined rails 94, which are partially supported by the housing 18. As the arm 30 is pivotally rotated by the hydraulic motor 32, the arm 30 actuates movement of a stop means 97 provided with a protuberance 98 on each side of the rails 28 adapted to engage the shaft 22 of an armature core 20. The stop means 97 is pivotally mounted upon a pin 99 adjacent the lower ends of the rails 28. With each movement of the arm 30, the stop means 97 pivots about the pin 99 and allows one armature core 20 to roll downwardly and into the arcuate recess at the end of the arm 30. A roller 100, rotatively attached at the end of the stop means 97 engages the curved surface 101 of the arm 30.

A switch 102, positioned between the rails 28, is used

5 to indicate to the machine control system that an armature core 20 has rolled into the arcuate recess of the arm 30 and is ready to be carried to the chuck 50.

6 A limit switch 103, positioned between the rails 94 is used to indicate to the control system of the machine that the supply of insulated armatures upon the rails 94 has become so great that armatures are positioned one against the other upon the rails 94 extending up to the limit switch 103. Receiving such an indication from the switch 103, the control system will stop the machine from operation until the line of insulated armatures upon the rails 94 becomes shorter.

7 A dash pot mechanism 104, having a piston rod 105, is attached to the hydraulic motor 32, which assists in smoothing the operation of the hydraulic motor 32.

8 A preferred modification of the automatic insulating machine of this invention is shown in FIGURES 8, 9 and 10. Armature cores to be insulated roll downwardly upon a plate 109 and between a pair of inclined guide rails 110 toward a housing 111.

9 A hydraulic motor 112 attached to the housing 111 by a pair of plates 113 and a bolt 115 is provided with a piston rod 114, and reciprocally moves a link 116 to which is attached two pairs of control fingers 118 and a pair of control fingers 120. Upon each operation of the hydraulic motor, the control fingers 118 allow one armature core 20 to roll downwardly into a clamping means. An insulated armature core 20, which is held by the fingers 120, acts as an abutment and stops the downward movement of an uninsulated armature core, so that the shaft 22 of the uninsulated core is in position to be grasped by a movable clamping member 124 and retained in a clamp 126.

10 A short section of one of the guide rails 110 is removed at the location at which an armature core 20 is clamped by the clamping finger. This permits direct longitudinal movement of an armature from the point at which it is clamped. Clamping member 124 is attached by means of an arm 129 to a piston rod 130 of a hydraulic motor 132. Clamp 126 is attached to an extension arm 131. The hydraulic motor 132 and the extension arm 131 are attached to a plate 134 which is movably guided by a pair of rods 136. The plate 134 is attached to a piston rod 140 by a connector 141.

11 The piston rod 140 is operated by a hydraulic motor 142. The hydraulic motor 142 and the rods 136 are supported upon a base 143. The hydraulic motor 132 provides power for the clamping action upon the shaft 22 of the armature core 20. The hydraulic motor 142 actuates movement of a clamped armature core 20 longitudinally into a chuck 144 in the housing 111. The armature core 20 is partially inserted into the chuck 144 which is an integral part of the housing 111. The chuck 144 is similar to the arcuate clamping recess 50 shown in FIGURE 1, and is adjacent an insulating device in the housing 111. Said insulating device is similar to that disclosed in the housing 18 shown in FIGURES 4, 5, 6 and 7.

12 The clamping members 124 and 126 retain a grasp upon one end of the shaft 22 of the armature core 20 while the armature core 20 is so positioned in the chuck or clamping recess 144. The core 20 is automatically provided with insulation in each slot 24 in a manner similar to that described with respect to the preferred embodiment, and the hydraulic motor 142 is then automatically actuated to move the armature core 20 longitudinally from the chuck 144 back to the rails 110. The hydraulic motor 132 is then automatically actuated by the controls of the machine to unclamp the shaft 22. The hydraulic motor 112 is then automatically operated, actuating movement of fingers 118 and 120 allowing each armature core 20 positioned on the rails 110 to roll farther down the rails 110.

13 The term hydraulic motor as used in this description is construed to include any type of fluid operable motor. Means for automatically controlling the operation of the

moving parts of this invention may consist of any suitable control system. The particular operation disclosed may be more readily adapted to an electrical control system but any other suitable type of control means such as mechanical or fluid control results in successful operation of this invention.

This invention can be used for other purposes than insulating. It can be adapted to perform any one of many types of work upon an article retained in the chuck.

A machine of this invention can be used in a large insulating and winding system in which, for example, a plurality of insulating machines supply insulated armatures to a plurality of armature winding machines. The automatic means provided permits operation of all machines in the system to their full capacities without the necessity of manually operating control.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A machine for automatic seriatim operation upon rotors, each of which has a shaft, comprising a chuck, a pair of inclined rail guide members adjacent the chuck, an inclined plate disposed substantially between and slightly below the rail guide members and being adapted to support a series of rotors carried in rolling position between the rail guide members with the shafts of the rotors in parallel relation, the rail guide members being adapted to direct the rotors to a position adjacent the chuck, motor operated abutment members movable adjacent the rails and engageable with the shaft of a rotor which is disposed adjacent said position the abutment members being movable to positions out of engagement with shafts of the rotors to permit downward rolling movement of the rotors upon the plate, motor operable clamping means engageable with a shaft of a rotor in said position, means for moving said clamping means so that a rotor is moved in an axial direction between said position and said chuck while the rotor shaft is held by the clamping means, and means for operation upon a rotor while the rotor is in said chuck.

2. A machine for automatic seriatim operation upon rotors, each of which is provided with a shaft, comprising a pair of inclined guide rails, an inclined support member adjacent the rails for support of rotors disposed between the rails, a chuck adjacent the rails, a portion of said support member being located so that it is adapted to support a rotor substantially in alignment with the chuck, motor operated abutment members adjacent the rails and engageable with a shaft of a rotor disposed on said support member and adjacent said portion, there being abutment members to prevent rolling of a rotor to said portion and an abutment member to engage the shaft of a rotor which has rolled downwardly from said portion, means for moving the abutment members to positions out of engagement with the rotor shafts to permit downward rolling movement of the rotors, motor operated clamping means engageable with the shaft of a rotor on said portion of the support member, means for moving the clamping means and a rotor from said portion to said chuck and to return the rotor to said portion of the support member, and means operable upon a rotor disposed in said chuck.

3. In a machine for seriatim operation upon rotors each of which is provided with a shaft, support structure, a chuck carried by the support structure, inclined conduit means carried by the support structure and disposed adjacent the chuck, the inclined conduit means being adapted to direct rotors to and from a position in substantial alignment with the chuck, motor operable abutment means

adjacent the conduit means and adjacent said position, the abutment means being engageable with a shaft of a rotor before the rotor reaches said position and engageable with a shaft of a rotor after the rotor leaves said position, a motor carried by the support structure, a carrier attached to the motor and reciprocally movable in between said position and said chuck, motor operated shaft clamping means attached to said carrier so that a shaft of a rotor at said position is clamped and the rotor is moved to the chuck by the carrier and returned to the chuck by the carrier while the shaft of the rotor is clamped by the clamping means.

4. In a machine for automatic seriatim operation upon rotors each of which has a shaft, support structure, a chuck carried by the support structure, an inclined track carried by the support structure adjacent the chuck, the inclined track being adapted to support a series of rotors as the rotors are disposed in rolling position thereupon with the shafts of the rotors parallel, the track having a loading section from which a rotor is axially movable into the chuck and to which the rotor is returned after operation thereupon in the chuck, a first fluid motor, the first fluid motor being carried adjacent the track and having a piston rod axially movable substantially parallel to the track, a link attached to the piston rod and movable therewith, a plurality of control fingers pivotally attached to the link, there being at least two control fingers engageable with the shafts of rotors adjacent said loading section and upwardly on the track before the rotors reach said loading section, the abutment fingers thus preventing the engaged rotor from moving to the loading section, subsequent rotors disposed upwardly on the track being in engagement one with the other in seriatim relation as they are prevented by a rotor which is engaged by a control finger from further movement downwardly upon the track, at least one control finger carried by said link and extending to a position adjacent the track downwardly from said loading section, the last said control finger being engageable with a shaft of a rotor after the rotor leaves said loading section, thus preventing further movement of the rotor downwardly upon the track, a second fluid motor carried by the support structure, a clamping member attached to the second fluid motor and movable between said loading section of the track and said chuck, a third fluid motor, the third fluid motor being attached to said clamping means for operation thereof, the clamping means being engageable with a shaft of a rotor disposed at said loading section of the track, the rotor thus being moved to and from the chuck by said second fluid motor, the third fluid motor clamping and unclamping the shaft of the rotor when the rotor is so positioned at the loading section, said first fluid motor operating to move said link, each of the control fingers pivotally moving from a position to engage a shaft to a position out of engaging position as the link moves in one direction, each of said control fingers pivotally moving from disengaging position to engaging position as the link moves in the opposite direction.

5. A machine for automatic seriatim operation upon rotors, each of which has a shaft, comprising a chuck, a pair of inclined rotor guide means adjacent the chuck, an inclined support underlying the guide means and being adapted to support a series of rotors carried in rolling position upon the inclined support with the shafts of the rotors in parallel relation, the guide means being adapted to direct the rotors in a position adjacent the chuck, motor operated abutment members movable adjacent the guide means and engageable with the shaft of a rotor which is disposed adjacent said position, the abutment members being movable to positions out of engagement with shafts of the rotors to permit downward rolling movement of the rotors upon the support, motor operable clamping means engageable with a shaft of a rotor in said position, means for moving said clamping means so that a rotor is moved in an axial direction between said position and

said chuck while the rotor shaft is held by the clamping means, and means for operation upon a rotor while the rotor is in said chuck.

6. A machine for automatic seriatim operation upon rotors according to claim 5, wherein the rotor adjacent the chuck abuts the rotor previously operated upon, and wherein hydraulically driven fingers engage the shaft of the previously operated rotor.
